2,326,875

TRAFFIC SIGNAL

Alfred McKinley Miles, Spartansburg, S. C.

Application October 22, 1940, Serial No. 362,264

1 Claim. (Cl. 177—327)

This invention relates to traffic signal light construction, the primary object of the invention being to provide a traffic light embodying the required number of lamps mounted in a single lamp housing, eliminating the necessity of providing separate lamp housings or compartments for the various colored lights constituting the signal, thereby reducing the cost of traffic signals to the minimum.

An important object of the invention is to provide a traffic light embodying a plurality of fluorescent tubes installed in a single lamp housing, and constructed in such a manner that the ultra-violet light furnished by the arc streams within the individual tubes, will project various colored light rays for signalling purposes.

Another object of the invention is to provide a signal housing wherein the yellow warning signal may overlap the green signal, without the use of multiple lenses and reflectors.

Still another object of the invention is to provide a signal which does not require the shifting of the line of vision of the motorist, in order to follow the signal changes.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a side elevational view of a traffic signalling light, constructed in accordance with the invention.

Figure 2 is a longitudinal sectional view therethrough.

Figure 3 is a sectional view taken on line 3—3 of Figure 2.

Figure 4 is a view illustrating the red signal, as being displayed.

Figure 5 is a view illustrating the green signal.

Figure 6 is a view illustrating the area of the lens illuminated, when the tube in the annular light compartment, is illuminated.

Referring to the drawings in detail, the lamp housing is indicated generally by the reference character 5 and is provided with the usual hood 6, to obscure the signals, from one direction.

The lamp housing is provided with an open end, normally closed by means of the lens 7, which is held in position between the annular flanges 8, which grip the edge of the lens. Extending from the outer surface of the lamp housing 5, and spaced therefrom, is a flange 9 which is constructed of reflecting material, the flange 9 being arranged to provide an annular lamp com-

partment 10 surrounding the open end of the housing 5.

Mounted within the annular lamp compartment 10, is a spirally arranged fluorescent tube constructed in such a way that electric current supplied to the tube, will cause a light of yellow character, to be projected therefrom. Arranged within the lamp housing, and disposed adjacent to the open end thereof, is a spirally formed 10 neon tube 11, and adjacent to the neon tube 11, is a fluorescent tube 12 which is of a character to project green light rays through the open end of the housing 5. Transformers indicated at 13 are positioned in the base 14 of the lamp housing, the base 14 being secured to a supporting post which is indicated at 15, by means of the straps 16.

It will of course be understood that suitable time-controlled switches not shown, are used in conjunction with the signal light, in the usual and well known manner, so that the various lights will be turned on consecutively.

From the foregoing it will be seen that due to the construction shown and described, a single lamp housing is provided for containing the three distinct signals for signalling traffic, thereby eliminating the necessity of providing three separate compartments or lamp housings to accomplish the signalling result, and consequently reducing the cost of traffic signals to a minimum.

It will also be seen that because an annular light chamber is provided adjacent to the open end of the main lamp housing, the yellow warning signal may operate to overlap the green signal, without the use of multiple lenses and reflectors.

What is claimed is:

In a traffic light, a main lamp housing having an open end, a flange constructed of reflecting material secured to the housing exteriorly thereof, said flange extending outwardly and forwardly towards the open end of the housing, said flange being spaced from the housing providing an annular lamp compartment adjacent to the open end of the lamp housing, the outer end of the lamp housing extending beyond the outer end of the annular lamp compartment, independent fluorescent light tubes of distinctive colors, mounted within the annular lamp compartment 40 and the main lamp housing, whereby each light tube will illuminate the lamp housing in which it is positioned, with its distinctive color, when the tubes are energized, creating a signal, a curved lens positioned over the outer end of the main lamp housing and contacting the outer edge thereof, and said lens being of a diameter to extend over the outer end of the annular lamp compartment, closing the annular lamp compartment.
